US00D734166S

(12) **United States Design Patent**
Olson et al.

(10) **Patent No.:** US D734,166 S
(45) **Date of Patent:** ** Jul. 14, 2015

(54) **FILL POUCH ASSEMBLY FOR
ENCAPSULATION DEVICE**

(71) Applicant: **ViaCyte, Inc.**, San Diego, CA (US)

(72) Inventors: **Erik Olson**, San Diego, CA (US);
Michael Scott, San Diego, CA (US);
Donald Koenig, San Diego, CA (US)

(73) Assignee: **VIACYTE, INC.**, San Diego, CA (US)

(**) Term: **14 Years**

(21) Appl. No.: **29/488,217**

(22) Filed: **Apr. 16, 2014**

(51) LOC (10) Cl. **09-05**

(52) U.S. Cl.

USPC **D9/707**

(57) **CLAIM**

The ornamental design for fill pouch assembly for encapsulation device, as shown and described.

DESCRIPTION

FIG. 1 is a perspective view of the DFPA from above the DFPA looking down;

FIG. 2 is a perspective view of the DFPA illustrated in FIG. 1 from below the DFPA, looking up;

FIG. 3 is a top plan view of the DFPA illustrated in FIG. 1;

FIG. 4 is a bottom plan view of the DFPA illustrated in FIG. 1;

FIG. 5 is a left side elevation of the DFPA illustrated in FIG. 1;

FIG. 6 is a right side elevation of the DFPA illustrated in FIG. 1;

FIG. 7 is a back view of the DFPA illustrated in FIG. 1; and,

FIG. 8 is a front view of the DFPA illustrated in FIG. 1.
